Inventor
Edwin Illig

By his Attorney

M. H. Lockwood

UNITED STATES PATENT OFFICE.

EDWIN ILLIG, OF NEW YORK, N. Y.

PUTTY-SUBSTITUTE STRIP.

Application filed June 29, 1921. Serial No. 481,301.

To all whom it may concern:

Be it known that I, EDWIN ILLIG, a citizen of the United States, and resident of New York, county and State of New York, have invented certain new and useful Improvements in Putty-Substitute Strips, of which the following is a specification.

My invention relates more particularly to an article of manufacture comprising a flexible plastic or semi-plastic strip of material of suitable cross-section for holding glass in a window sash in place of putty and the method of forming the same. It is well known that putty ultimately dries up and then more readily becomes cracked or broken loose from the sash and glass and in a short time must be replaced. Not every householder has a supply of putty on hand and to buy it in the stores for small repair jobs it is expensive and if an excess quantity is bought, it cannot be kept for any length of time for future use.

As a matter of economy, therefore, and for the purpose of providing a durable and effective substitute for putty, I have prepared strips of felted or other suitable material impregnated with a suitable waterproofing compound and covered with a layer of weather-proof material, which may be composed of a bituminous compound or any material found suitable for the purpose.

The object, of course, is to make a putty-substitute strip, which shall be as effective in retaining the glass in the sash as putty and at the same time be less likely to deteriorate and may be so marketed that the householder may obtain the exact quantity required or if a surplus is obtained it may be stored away and kept indefinitely for future use.

It is further contemplated to manufacture and market the strips in standard lengths with the ends mitered, for this will save the user from the trouble and bother of attempting to cut satisfactory mitered joints when placing the putty-substitute strips in the window sash. Miter joints are difficult to cut accurately without special tools and for this reason, it is preferable to supply the strips with the ends mitered. The strips may be supplied also in continuous lengths so that, if desired, the purchaser may obtain the strips in this manner and cut it up into the necessary lengths for use.

In order to further facilitate the use of my improved putty-substitute strips, they may be perforated at regular intervals longitudinally thereof, so that small rust proof nails or brads may be driven therethrough more readily than would otherwise be the case, thereby insuring a more neat appearing finished job.

My improved putty-substitute strip may be provided with a core formed of felted fibrous material, such as cotton, wood-fiber, cellulose, or any material that may be suitable for forming a water-proof semi-plastic strip. The strip thus formed may be made in part of woven fabric or built up of several plies of material and rolled or molded into the desired shape, after which it is preferably covered or coated with a layer of plastic weather-proof material, such as a suitable bituminous compound, rubber, or other suitable material, adapted to give the necessary qualities of durability and plasticity required in a putty-substitute strip, and obviously, the strips may be made in any suitable or desired colors by incorporating in the covering the necessary pigments.

My improved putty-substitute strip is more particularly shown in the accompanying drawings, which illustrate one form and adaptation of my improvement. In the accompanying drawings, Fig. 1 represents a window sash, in which the glass is held in place by my putty-substitute strips; Fig. 2 represents a set of the strips perforated and cut to the desired lengths, the strips being provided with mitered ends; Fig. 3 is a sectional detail of the window sash taken on the line 3-3 of Fig. 1; Fig. 4 is an enlarged perspective sectional view of one of the strips; Fig. 5 is a plan view of a continuous strip in coiled form and Fig. 6 is an enlarged cross-sectional view of a strip of modified construction.

Referring to the drawings, the window sash is represented at 1 and the panes of glass 2 are held in place by my improved putty-substitute strips 3, which are secured in place by brads or nails 4.

The putty-substitute strips preferably comprise a core 5 (see Figs. 3 and 4) which may be composed of cheap cotton felt or other suitable felted fibrous material and impregnated with a suitable water proof-

ing compound. The core 5 is then preferably given a coating or covering 6 of bituminous or the like material for rendering the strip weather-proof. The strip thus formed is plastic or semi-plastic and pliable and may be molded or shaped to readily fit the angle between the glass and the sash as indicated in Fig. 3 of the drawings. The putty-substitute strip may be molded or formed so that the angle 7 of the strip is preferably slightly greater than at right angle, so that it will pack tightly between the glass and the window sash and form watertight joints therebetween. In the form shown, the strips are indicated as triangular in cross-section, but obviously they may be made quarter-round or any other suitable or desired shape.

In order that the strips may be available for immediate use by the purchaser and to enable the user to obtain satisfactory results and secure a neat appearing job, the strips may preferably be supplied in standard cut lengths (Fig. 2) with the ends mitered as indicated at 8 in Fig. 2 of the drawings. The cut strips when supplied in this manner may be sold in the packages containing one or more sets with rust-proof nails which may be obtained by the householder for immediate use, or because of the comparative indestructibility of the strips, a supply of them may be kept on hand for use at any time the occasion may arise. If the standard lengths of mitered strips on hand happen to be too long, they may be cut in two and a section taken out of the middle, thus saving the mitered ends of the strips, and the pieces made to fit the window glass and fastened in the sash, the cut ends being buttjointed and secured by brads or nails as indicated at 9 in Fig. 1 of the drawings.

The strips may also be supplied as indicated in Fig. 5 of the drawings in continuous lengths and the user may cut off the desired lengths and miter the ends, for since the material is more or less plastic and soft, it may readily be cut with an ordinary pocket knife, and in using up any scraps or short pieces the joints may be made as indicated at 9, and the material packed or molded, so as to be practically invisible and perfectly tight, for the material may be sufficiently plastic for this purpose. In this manner, it will be understood that small pieces and ends may be utilized, so that no waste of material need occur in using my improved putty-substitute strips. The longer strips can also be cut down.

In marketing the putty-substitute strips, it may be considered desirable to not only supply the strips in standard lengths with mitered ends, but also to perforate them with small holes as indicated at 10, uniformly spaced length-wise thereof, in order

to facilitate fastening the strips in the window sash. Strips perforated in this manner are more readily attached and the spacing between the brads or nails will be more uniform, and there will be less likelihood of the user distorting the material or unnecessarily puncturing or rupturing the weather-proof coating, thereby securing a better finished and neater job than would be likely to obtain if the position of the securing brads were left entirely to the guess work of the user. It will be understood, however, that the strips may be supplied either in cut lengths or in continuous lengths without perforations and without mitered ends.

It will be obvious that the putty-substitute strips may be made not only in any cross-sectional shape, but may be made in any desired width and size to meet the demand for various purposes and various sizes of window glass or sash and for some of the larger sizes, it may be desirable to strengthen the core by incorporating therein strips of suitably woven thin fabric, as indicated at 11 in Fig. 6 of the drawings. It also may be desirable to utilize strips of tough paper for the same purpose or any other suitable material, which combined with the felted material may be rolled and molded to the desired shape as indicated, or otherwise utilized to form and strengthen the core. In any case, the core and covering layer 6 may be compact and firm but preferably is formed sufficiently plastic or semi-plastic to readily pack into the joint between the sash and the glass, and thereby form weather-proof joints both between the sash and glass and the strip.

It will be obvious that putty-substitute strips of this character may be made in sheet form and cut into strips and rolled folded and molded into the desired shape, or they may be formed by rolling or drawing the material into the desired shape and thereafter coating it with the bituminous weather-proof material or the like, substantially as shown and described.

While I have shown the preferred form and shape of my improved putty-substitute strip, it will be understood that various modifications in the structural details and the preparation of the strips may be made, and various materials suitable for the purpose may be employed, both for the core and for the weather-proof covering without departing from the spirit and scope of the invention.

I claim:

1. The method of preparing a putty-substitute strip, which comprises impregnating a strip of pliable porous material with a water-proofing compound and covering the strip thus formed with a layer of plastic weather-proof material.

2. The method of forming a putty-substitute strip, which comprises impregnating a strip of felted fibrous material with a water-proofing compound, then forming the strip into the desired shape, then covering it with a layer of plastic weather-proof material.
3. The method of forming a putty-substitute strip, which comprises impregnating a strip of felted material with a water-proofing compound, then covering it with a layer of bituminous weather-proof compound, the strip being plastic and adapted to be shaped to the desired cross-section.
4. The method of forming a putty-substitute strip, which comprises impregnating felted material with a water-proofing compound, then cutting said material into strips, then giving the strips the desired cross-sectional shape, then coating the strips with a bituminous weather-proof compound.
5. A putty-substitute strip comprising a plastic core of felted material impregnated with a water-proof compound and a covering therefor of plastic weather-proof material.
6. A putty-substitute strip comprising a core of felted fibrous material impregnated with a water-proof compound, and a layer of bituminous weather-proof compound covering said core, the strip being plastic before and after covering.
7. A putty-substitute strip comprising a core of fibrous plastic water-proofed material molded into the desired shape and covered with a layer of plastic bituminous material.
8. As an article of manufacture, a putty-substitute strip for securing glass in the sash, comprising a flexible plastic weather-proof strip, provided with mitered ends, 40 said strip being provided at intervals with perforations therethrough for securing the strip to the window sash, said strip being cut to a length conforming with standard glass dimensions. 45
9. As an article of manufacture, a putty-substitute strip, comprising a plastic core of impregnated water-proof felt, surrounded and enclosed by a plastic bituminous compound for weather-proofing the same, said 50 strips being provided with mitered ends and perforated at intervals for securing the same to the window sash.
10. In combination with a window sash, a putty-substitute strip of flexible plastic 55 weather-proof material provided with mitered ends, said strip being perforated at intervals, and means utilizing said perforations for securing the strip to the sash.

EDWIN ILLIG.
